UNITED STATES PATENT OFFICE

150,773

DESIGN FOR A LADY'S EMBLEMATIC CAP

Bertie J. Johnson, San Luis Obispo, Calif.

Application March 6, 1947, Serial No. 137,387

Term of patent 14 years

(Cl. D3—13)

To all whom it may concern:

Be it known that I, Bertie J. Johnson, a citizen of the United States, residing at San Luis Obispo, in the county of San Luis Obispo and State of California, have invented a new, original, and ornamental Design for Lady's Emblematic Cap, of which the following is a specification, reference being had to the accompanying drawing, forming part thereof.

In the drawing:

Fig. 1 is a front elevation of the lady's emblematic cap, showing my new design.

Fig. 2 is a side elevation from the right as seen in Fig. 1.

Fig. 3 is a top plan view.

Fig. 4 is a side elevation from the left as seen in Fig. 1.

I claim:

The ornamental design for a lady's emblematic cap, substantially as shown.

BERTIE J. JOHNSON.
